H. M. YOUNG

WIRE FAERIC

Filed Sept. 26, 1921

INVENTOR

HARRY M. YOUNG,
by Ralph Kaelin ATTORNEY.

UNITED STATES PATENT OFFICE.

HARRY M. YOUNG, OF ST. LOUIS, MISSOURI, ASSIGNOR TO WESTERN WIRE PRODUCTS COMPANY, OF ST. LOUIS, MISSOURI, A CORPORATION OF MISSOURI.

WIRE FABRIC.

Application filed September 26, 1921. Serial No. 503,209.

To all whom it may concern:

Be it known that I, HARRY M. YOUNG, a citizen of the United States, residing at the city of St. Louis, State of Missouri, have 5 invented a certain new and useful Improvement in Wire Fabrics, of which the following is a specification, reference being had to the accompanying drawings, forming a part thereof.

10 This invention relates generally to wire fabrics and, more particularly, to a certain new and useful improvement in wire fabrics of the knitted type especially adapted for use in the production of spring-mattresses 15 for beds and the like, the principal object of my present invention being to provide a single wire knitted fabric whose construction is simple and inexpensive and which will minimize "sagging" or distortion under- 20 use.

With the above and other objects in view, my present invention resides in the novel features of form, construction, arrangement, and combination of parts hereinafter described and afterwards pointed out in the claims.

In the accompanying drawing,

Figure 1 is a plan view of a spring-mattress embodying a section of knitted wire fabric constructed in accordance with my invention; and

Figure 2 is a longitudinal sectional view of the mattress and fabric taken approximately on the line 2—2, Figure 1.

35 Referring now more in detail to the said drawing, which illustrates a practical embodiment of my invention and in which like reference characters refer to like parts throughout the several views, A designates 40 the single wire or strand of the knitted portion of the structure, whose terminals B and C are relatively fixed, and which is fabricated as by knitting to form an approximately square mesh body comprising loops D in 45 spaced parallel rows extending in one direction or longitudinally of the fabric and loop-spacing strands or laterals E extending at a right angle to the loops D, whereby each 50 of the meshes of the fabric, that is to say, each of the meshes of the fabric except at the longitudinal and lateral sides thereof, comprises a pair of the loops D and a pair of the spacing strands E.

Each so-called inside loop D comprises 55 integrally a relatively sharp bight 1, a pair

of suitably elongated legs or longitudinals 2—2 extending in approximately straight lines from the bight 1, and oppositely disposed turns or bends 3—3 at the ends of each leg or longitudinal 2 opposite the bight 1, each intermediate loop of a row, that is to say, each loop of a row except the end loops of the row, having engagement at its bight with the bends of the next adjacent loop of such row.

60 Each loop-spacing strand or lateral E consists of a single length or section 4 of the wire integrally extending in an approximately straight line between spaced pairs of the turns or bends 3 of the loops D.

65 As so fabricated, the fabric as a whole is bounded at one longitudinal end by a margin comprising the bights 1 of a series of the spaced loops D; at its opposite longitudinal end by a margin comprising the 70 bends or turns 3 and the loop-spacing strands or laterals 4 opposite the bights 1; at one lateral side by a margin comprising the terminals B and C, bights 1, and loops F, the latter being substantially like the 75 main body loops D, with the exception, however, that its one leg 2' is of double the length of the corresponding leg of the loops D in the body of the fabric, whereby its bight 1 and bend or turn 3 are spaced by a 80 length comprehending three of the laterals 4, and its other leg 2'' is joined by an oblique lateral 4' to the next row of loops D; and on the other lateral side by a substantially similar side margin comprising 85 similarly extended legs 2', all as best seen in Figure 1.

80 The fabric, knitted of a single wire to thus comprise straight lines in both the longitudinals and laterals, as distinguished from the substantially circular loops in rows or chains, as is common to the present knitted fabrics, is one which may not only be readily fabricated, but which will also be practically free from distortion or stretching.

90 The supporting structure for my new fabric for its adaption for use in a spring-mattress, bed, or the like, comprises heads 95 5 and rails 6 suitably secured together and which I prefer to construct of angle iron, as shown. To the heads 5, are attached a number of coil-springs 7 or other suitable yielding members, the springs 7 at one longitudinal end being secured in the bights 1 of the loops D and the other longitudinal end en- 100 105 110

gaging around the bends or turns 3 between the legs 2 of the loops D and the loop-spacing strands 4. In this manner, the rows or chains of loops D and the series of laterals 5 E are yieldingly supported relatively to the heads 5.

At the side margins paralleling the rows or chains of loops D, I provide flat band edge or so-called "sag" or floating rails 8—8' 10 each secured at its opposite ends to the heads 5 by means of springs 9, and to which rails the knitted fabric as a whole is suitably secured. Obviously various means may be conveniently employed for such purpose. 15 In the present instance, I employ for such purpose as shown the securing-bands or links 10 engaging the fabric and the rail 8 at one side margin and at the other side margin engage the fabric with the rail 8' by, 20 in the assembling of the spring-mattress or bed, inserting the rail through the edge-loops F between their elongated legs 2' and the oblique laterals 4'. In the present instance, I have also shown the terminals B 25 and C of the fabric as secured, and thereby "fixed", in the springs 9, but obviously the terminals of the fabric may be otherwise relatively "fixed", as, for instance, to the body of the fabric itself or to the sag-rail, 30 and other changes in the form, construction, arrangement, and combination of the several parts of my fabric may be made and substituted for those herein shown and described without departing from the nature and principle of my invention. 35

Having thus described my invention, what I claim and desire to secure by Letters Patent is:

1. A substantially square-mesh knitted fabric constructed of a single metallic wire and integrally including a plurality of longitudinal rows of loops and a plurality of laterals for spacing the longitudinal rows of loops, each inside loop of the fabric 40 including a bight, a pair of substantially parallel legs extending in approximately straight lines from the bight, and oppositely disposed bends at the end of each leg opposite the bight, and each lateral consisting of a single length extending in approximately a straight line between pairs of the 45 bends of the loops, each intermediate loop of a row extending at its bight under the legs and over the bends of the next adjacent 50 loop in such row and each outside loop at

the lateral sides of the fabric having one leg of a length double the length of the other leg thereof, each inside mesh of the fabric comprising a pair of loops and a pair of the loop-spacing laterals, some of the 60 laterals at one lateral side of the fabric being obliquely disposed to the remaining laterals and providing open sag-rail accommodating edge loops at said lateral side of the 65 fabric.

2. A substantially square-mesh knitted fabric constructed of a single metallic wire and integrally including a plurality of longitudinal rows of loops and a plurality of laterals for spacing the longitudinal rows 70 of loops, each inside loop of the fabric including a bight, a pair of substantially parallel legs extending in approximately straight lines from the bight, and oppositely disposed bends at the end of each leg opposite the bight, and each lateral consisting of a single length extending in approximately a straight line between pairs of the bends 75 of the loops, each intermediate loop of a row extending at its bight under the legs 80 and over the bends of the next adjacent loop in such row and each inside mesh of the fabric comprising a pair of the loops and a pair of the loop-spacing laterals, some of the laterals at one lateral side of the 85 fabric being obliquely disposed to the remaining laterals and providing edge loops at said lateral side of the fabric, in combination with a supporting structure comprising suitably connected end and side 90 bars, springs engaging one end bar of the supporting-structure and the bights of the adjacent end row of loops, springs 95 engaging the opposite end bar of the supporting-structure and the bends of the opposite end row of loops, a sag-rail attached at one lateral margin of the fabric to the opposite end-bars of the supporting structure, links having engagement with said sag-rail and with the outside rows of loops upon 100 said lateral side of the fabric, and a second sag-rail projecting lengthwise through said edge loops upon the other lateral side of the fabric and also attached at its ends to the opposite end-bars of the supporting structure. 105

In testimony whereof, I have signed my name to this specification.

HARRY M. YOUNG
